COMBINATION RAZOR AND BLADE HOLDER OR SIMILAR ARTICLE

Melvin Franklin Bourne, Ravenswood, W. Va.

Application April 10, 1957, Serial No. 45,670

Term of patent 14 years

(Cl. D4—3)

Figure 1 is a front elevational view of a combination razor and blade holder or similar article, showing my new design.

I claim:

The ornamental design for a combination razor and blade holder or similar article, as shown.
